PICTURE FRAME MOULDING

Johannes Vihma, Toronto, Ontario, Canada, assignor to Artistic Woodwork Co. Ltd., Downsview, Ontario,
Canada

Filed Jan. 8, 1973, Ser. No. 322,089

Term of patent 14 years

Int. Cl. D6—07

U.S. Cl. D6—246

The figure is a perspective view of a picture frame moulding showing my new design, a portion thereof being broken away to indicate indeterminate length.

I claim:

The ornamental design for a picture frame moulding, as shown and described.
